(57) **CLAIM**

The ornamental design for a mobile terminal with camera as shown and described.

DESCRIPTION

FIG. 1 is a front view of a mobile terminal with camera, in an unfolded state with a camera retracted therein, showing my new design;

FIG. 2 is a back view of FIG. 1;

FIG. 3 is a left view of FIG. 1;

FIG. 4 is a right view of FIG. 1;

FIG. 5 is a top view of FIG. 1;

FIG. 6 is a bottom view of FIG. 1;

FIG. 7 is a top, front and right side perspective view of FIG. 1;

FIG. 8 is another front view of the mobile terminal with camera, in an unfolded state with a camera protruded;

FIG. 9 is a back view of FIG. 8;

FIG. 10 is a left view of FIG. 8;

FIG. 11 is a right view of FIG. 8;

FIG. 12 is a top view of FIG. 8;

FIG. 13 is a bottom view of FIG. 8;

FIG. 14 is a top, front, and right side perspective view of FIG. 8;

FIG. 15 is a front view of the mobile terminal with camera, in a folded state with a camera retracted therein;

FIG. 16 is a back view of FIG. 15;

FIG. 17 is a left view of FIG. 15;

FIG. 18 is a right view of FIG. 15;

FIG. 19 is a top view of FIG. 15;

FIG. 20 is a bottom view of FIG. 15;

FIG. 21 is a top, front, and right side perspective view of FIG. 15;

(Continued)

FIG. 22 is another front view of the mobile terminal with camera, in a folded state with a camera protruded; FIG. 23 is a back view of FIG. 22; FIG. 24 is a left view of FIG. 22; FIG. 25 is a right view of FIG. 22; FIG. 26 is a top view of FIG. 22; FIG. 27 is a bottom view of FIG. 22; FIG. 28 is a top, front, and right side perspective view of FIG. 22; FIG. 29 is a front view of the mobile terminal with camera, in a reversely folded state with a camera retracted therein; FIG. 30 is a back view of FIG. 29; FIG. 31 is a left view of FIG. 29; FIG. 32 is a right view of FIG. 29; FIG. 33 is a top view of FIG. 29; FIG. 34 is a bottom view of FIG. 29; FIG. 35 is a top, front, and right side perspective view of FIG. 29; FIG. 36 is another front view of the mobile terminal with camera, in a reversely folded state with a camera protruded; FIG. 37 is a back view of FIG. 36; FIG. 38 is a left view of FIG. 36; FIG. 39 is a right view of FIG. 36; FIG. 40 is a top view of FIG. 36; FIG. 41 is a bottom view of FIG. 36; and, FIG. 42 is a top, front, and right side perspective view of FIG. 36.

The broken lines in the figures illustrate portions of the mobile terminal with camera that form no part of the claimed design.
